[57] CLAIM

The ornamental design for a pipe clamp hanger, substantially as shown.

DESCRIPTION

FIG. 1 is a perspective view of a pipe clamp hanger showing my new design;

FIG. 2 is a right side elevational view of the pipe hanger, the other side of FIG. 2 being a mirror image thereof;

FIG. 3 is a front elevational view thereof;

FIG. 4 is a rear elevational view thereof;

FIG. 5 is a bottom view thereof; and

FIG. 6 is a plan view thereof.

FIG. 1

FIG. 6

FIG. 4

FIG. 2

FIG. 3

FIG. 5
